(57) **CLAIM**

The ornamental design for a fitted sheet as shown and described.

DESCRIPTION

FIG. 1 is a top perspective view of a fitted sheet showing the new design;

FIG. 2 is a top view thereof;

FIG. 3 is a bottom perspective exterior view thereof;

FIG. 4 is a bottom view thereof;

FIG. 5 is a bottom perspective view of the fitted sheet of FIG. 1 in an alternate configuration, with the fitted sheet turned inside out;

FIG. 6 is a bottom view of the fitted sheet of FIG. 1 in an alternate configuration, with the fitted sheet turned inside out;

FIG. 7 is an enlarged view of the box of FIG. 6, of the fitted sheet of FIG. 1 in an alternate configuration, with the fitted sheet turned inside out;

FIG. 8 is an end view thereof; and,

FIG. 9 is a side view thereof.

1 Claim, 9 Drawing Sheets
